HOUSING FOR A VEHICULAR RADIO COMMUNICATION SYSTEM

Gene T. Brown, 2233 Cindy Court 32808, and William
B. Thompson, 3713 E. Kaley Ave. 32806, both of
Orlando, Fla.

Filed July 23, 1974, Ser. No. 490,932

Term of patent 14 years

Int. Cl. D14—03

U.S. Cl. D26—14 K

FIG. 1

FIG. 2

FIG. 3

FIG. 4

FIG. 5

FIG. 6

FIG. 1 is a front elevation view of a housing for a vehicular radio communication system showing our new design;

FIG. 2 is a rear elevation view of the design of FIG. 1;
FIGS. 3 and 4 are opposite side views of the design of FIG. 1;

FIG. 5 is a top plan view of the design of FIG. 1; and
FIG. 6 is a bottom plan view of the design of FIG. 1.
We claim:

The ornamental design for a housing for a vehicular radio communication system, as shown.
